UNITED STATES PATENT OFFICE.

LEWIS E. JORDAN, OF BAGLEY, IOWA, ASSIGNOR OF ONE-HALF TO OLIVER P. BEALE, OF SAME PLACE.

ADJUSTABLE SPOUT AND COVER FOR GRAIN-ELEVATORS.

SPECIFICATION forming part of Letters Patent No. 670,881, dated March 26, 1901.

Application filed September 7, 1900. Serial No. 29,281. (No model.)

To all whom it may concern:

Be it known that I, LEWIS E. JORDAN, a citizen of the United States, residing at Bagley, in the county of Guthrie and State of 5 Iowa, have invented a new and useful Adjustable Spout and Cover for Grain-Elevators, of which the following is a specification.

My object is to facilitate the delivery and distribution of grain from an elevator as required in transferring grain in bulk to load it in cars or wagon-boxes.

My invention consists in the manner of combining a hinged spout conveyer, a hinged cover, and a flexible tube with the wall and 15 fixed chute of an elevator-building, as herein-after set forth, pointed out in my claims, and illustrated in the accompanying drawings, in which—

Figure 1 is a vertical sectional view showing the construction, arrangement, and combination of all the parts, and dotted lines indicate the movements of the hinged spout conductor and hinged cover. Fig. 2 is a front face view showing the adjustable parts in 25 their normal positions.

The letter A designates the upright wall of a building, and B a chute extending outward through the wall.

C is a spout conveyer hinged to the wall, 30 and D is a frame fixed to the wall and open at its front to admit the lower end portion of the hinged spout conveyer. The top and rear side of the top end portion of the spout conveyer are open, and the open outer end of the 35 fixed chute extends into the open top end of said hinged conveyer.

F is a flexible tube adjustably and detachably connected with the lower free end of the rigid hinged conveyer C and adapted to be 40 turned in different directions as required for conveying and distributing grain in cars.

H is a cover hinged to the wall A above the chute B in such a manner that it will be self-

adjusting relative to movements of the hinged conveyer C and at all times rest upon the top 45 of said conveyer, as required, to keep its top closed.

Having described the purpose, construction, and application of my invention, its practical operation and utility will be readily understood by persons familiar with the art to which it pertains.

What I claim as new, and desire to secure by Letters Patent, is—

1. A grain-elevator building having a fixed 55 chute extending out through the upright wall, a spout conveyer hinged to the wall and provided with an opening on the rear side of its top portion to admit the end of the fixed spout and to allow adjustment relative to the spout 60 and the wall and to communicate with said chute and a self-adjusting cover hinged to the wall to extend over the fixed chute and the open top of the hinged conveyer, arranged and combined to operate in the manner set 65 forth for the purposes stated.

2. A grain conveyer and distributer comprising a fixed chute extended out through the upright wall of a building, a spout conveyer hinged to the outside of the wall and 70 provided with an opening in its back and top portion to admit the end of the fixed chute in its open top end and to allow it to be adjusted relative to the wall and fixed chute, a cover hinged to the wall above the hinged conveyer 75 and self-adjusting relative to movements of the conveyer and a flexible tube adjustably connected with the lower end of the spout conveyer, arranged and combined to operate in the manner set forth for the purposes 80 stated.

LEWIS E. JORDAN.
